PROGRAM DISTRIBUTION FOR TRAINS

Filed May 10, 1932

for the present I have not sought to claim the particular combination of elements or arrangement of parts as set forth in the claims, but I do claim as my invention the following: 1. A car having a radio receiver and a battery, a coil having a primary winding and a secondary winding, a condenser and a voltage regulating device, the coil being connected in series with the receiver, the primary winding being connected in shunt with the battery, the secondary winding being connected in shunt with the receiver, the condenser being connected in shunt with the receiver, and the voltage regulating device being connected in shunt with the receiver.

2. A car having a radio receiver, a battery, a coil having a primary winding and a secondary winding, a condenser and a voltage regulating device, the coil being connected in series with the receiver, the primary winding being connected in shunt with the battery, the secondary winding being connected in shunt with the receiver, the condenser being connected in shunt with the receiver, and the voltage regulating device being connected in shunt with the receiver.

UNITED STATES PATENT OFFICE

61

THE GOVERNMENT OF THE UNITED STATES OF AMERICA, BY AND WITH THE APPROVAL AND CONSENT OF THE ATTORNEY GENERAL, HAS GRANTED A PATENT TO THE INVENTOR, FOR THE INVENTION SET FORTH IN THE DRAWINGS AND SPECIFICATION.

2,008,279

PROGRAM DISTRIBUTION FOR TRAINS

Alva R. Hopkins, Merchantville, N. J., assignor to Radio Corporation of America, a corporation of Delaware

Application May 10, 1932, Serial No. 610,425

4 Claims. (Cl. 179—2.5)

62 My present invention relates to radio broadcast program distribution systems, and more particularly to program distribution systems especially adapted for trains.

63 One of the main objects of my present invention is to provide a system which is capable of receiving and distributing radio broadcast or local programs, such as recordings, or local microphone pick-up announcements, etc. on trains, the transmission from car to car being accomplished by the use of the conventional battery connections already available, insulation of the battery, generator and lighting circuit being accomplished by means of suitable arrangements of reactors and capacitors.

64 Another important object of the present invention is to provide a system for the reception and distribution of radio broadcast programs on trains, wherein existing lighting circuits of the train are utilized for transmitting the radio broadcast energy between cars, reactances being added in the lighting circuits in such a manner as to constitute a transmission line network with desired characteristics, such as, proper impedance, cut-off frequency and the like.

65 Another object of this invention is to provide a system for radio reception and distribution of radio programs on trains, which system utilizes existing battery connections between cars, has a

66 radio program transmission line, reactances being associated with the existing connections in such a manner that cars of a train not equipped for radio may be handled in regular manner without special attention as to the number of cars 30 and location in a train, it thereby being possible to couple a car not equipped for radio between radio equipped cars.

67 Still other objects of the present invention are to improve generally the simplicity and efficiency 40 of radio broadcast distribution systems for trains, and to especially provide a system which is not only reliable in operation, but economically installed in a train, and highly flexible in assembly when making up a train.

68 The novel features which I believe to be characteristic of my invention are set forth in particularity in the appended claims, the invention itself, however, as to both its organization and method of operation will best be understood by 50 reference to the following description taken in connection with the drawing in which I have indicated diagrammatically one circuit arrangement whereby my invention may be carried into effect.

69 In the accompanying drawing there is shown 55 in diagrammatic manner a radio broadcast pro-

gram distribution system primarily adapted for receiving and distributing radio broadcast programs on trains. The accompanying drawing only shows three cars of a train, it being understood that the rectangular boxes A, B and C, in dotted lines, represent independent cars of a train. Thus, car A is designated as the "Master receiver car"; car B is designated as a "Coupling car" and car C is designated as a "Radio-equipped car". That is to say, car A contains the receiving equipment for collecting a radio broadcast program, and changing the frequency of the collected energy to an audio or intermediate frequency, and distributing such resulting detected energy to such cars of the train which are equipped for program reproduction.

70 Car B is designated as a coupling car in view of the fact that it merely serves to transmit the energy to radio equipped cars, car B itself not being desired, for one reason or another, to be equipped with radio reproduction devices. It will thus be appreciated at the outset that the present system is highly flexible since the master receiver car may be situated at any point along the train, and that the non-radio equipped cars may be disposed in the train in any manner, since the so-called coupling cars readily transmit the energy from the master receiver car to all radio equipped cars.

71 The conductors 1, 2 represent the existing battery, generator and lighting circuit conductors common to all the cars in the train and running through all the cars of the train in proper conduit (not shown to preserve simplicity of disclosure). The conductor 1 represents the negative side of the existing power circuit of the train, while the conductor 2 represents the positive side of the said circuit. The lighting circuit L connected between the conductors 1, 2 of each car represents the conventional 32 volt light system of each car, the letter G designating the usual 32 volt storage battery connected in parallel with the light system L in each car between the conductors 1 and 2.

72 In shunt, in each car, with each battery G is connected the customary generator H, a condenser H' being connected in shunt with each battery G in order to by-pass the commutator ripple and static interference of generator H, and also to minimize the effect of changes in lighting load and changes in battery resistance. This condenser effectively grounds the low potential side of the network. The conventional representation K in series with each generator H designates the usual voltage regulation device. The condenser

H' is not a part of the existing circuit but a unit which is to be added to effectively ground one side of the transmission network.

Having now described the essential features of the existing battery cable circuit of a train, the master receiver car equipment will be explained. This equipment preferably comprises a conventional superheterodyne receiver having the antenna terminal and its input connected in the usual manner to an outside antenna, which antenna may be disposed on the roof of the master receiver car. The ground terminal of the receiver input may be grounded by connection to the grounded frame of the car, the latter preferably comprising the observation car and club car of a train, although it is to be clearly understood that the master receiver equipment may be disposed in any other car of a train.

The central receiver equipment is preferably a conventional superheterodyne receiver not employing a second detector and succeeding stages if intermediate frequency carrier is used, but if the entire audio range is to be transmitted, it is necessary to use the second detector and audio system of the receiver. However, if program reproduction is desired in the master receiver car, then the second detector and succeeding stages are to be employed in the master receiver car. Since the receiver employed in the master receiver car is of a conventional type, the various circuits thereof have been conventionally represented, as a radio frequency amplifier 3, a local oscillator 4, a first detector 5, and an intermediate frequency amplifier 6. Assuming that program reproduction is desired in the receiver car A, a second detector 7 is coupled to the output of the intermediate frequency amplifier, and an audio frequency amplifier 8 is utilized to amplify the audio frequency output of the second detector 7 to the proper audio level desired for the operation of the loudspeakers.

It is to be understood that the amplifiers 3, 6 and 8, may comprise one or more stages of amplification. In order to maintain the gain of the amplifier 3 of the receiver at a substantially uniform level, a conventional type of automatic gain control circuit 9 is utilized between the second detector and the amplifier 3 to control the gain of radio frequency amplification. It is not believed necessary to describe such a gain control circuit in detail, since the arrangement shown in the patent issued July 3, 1928 to Friis No. 1,675,848 may be utilized.

The circuits of the various components of the central receiver equipment are preferably energized from the 32 volt battery source G, through a power supply converter D which is connected in shunt across the terminals of the battery G. The dotted lines 10 designate the conductors supplying energizing power from the converter D. As stated heretofore, if program reproduction is desired in the master receiver car A, a second detector and audio frequency amplifier are connected to the output of the intermediate frequency amplifier 6. The audio output of the amplifier 8 is then distributed over a loudspeaker line 11, and a headphone line 12. The line 11 has coupled to it loudspeakers 13 located in such spaces of the car A which are public, while the headphones 14 are usually situated where individual reception is desired.

The audio frequency amplifier 8 should have sufficient amplification and power output to meet the requirements of one car, it being understood of course that the lines 11 and 12 are at differ-

ent volume level since the head phones do not require as great a power level as the loudspeakers. Furthermore, there may be coupled to the headphone line 12 so-called radio pillows 15 which comprise head phones disposed within an inflated pillow, or rubber padded pillow so that reception may be had while a person reclines. Such a radio pillow is disclosed by E. J. Quinby in his application Serial No. 412,044 filed December 6, 1929.

The output of the intermediate frequency amplifier 6 is, additionally, tapped by leads 16, 17 which connect the output of the amplifier 6 across the conductors 1, 2. In this way the amplified intermediate frequency energy of the central receiver may be distributed over the existing battery circuit conductors 1, 2 to radio equipped cars in the train. The system as described in the drawing involves the transmission of modulated intermediate frequency which would be approximately 175 kilocycles if a standard broadcast receiver is used. Therefore it is only necessary that the network be designed to transmit a relatively narrow band, say 170 to 180 kilocycles, or 165 to 185 kilocycles. More than one channel would require a correspondingly wider band. This is only necessary where the audio energy is being transmitted. In this case the second detector and audio amplifier of the broadcast receiver is used to amplify the audio frequency.

However, in order to insure proper transmission of such energy over the path comprising the conductors 1, 2, the battery, generator, and lighting circuit must be properly insulated from the radio equipment, and there must be added reactances of proper constants to the path 1, 2 such as to provide a transmission network of suitable impedance for the transmission of the central receiver output to the other cars of the train, and to additionally design the line network to give satisfactory transmission of the entire audio frequency range. This is accomplished by connecting inductive reactors 20, 21 in series in the conductive path 2, the common terminals of reactors 20, 21 being connected to the positive terminal of the battery G.

A capacitor 22, of suitable magnitude, is additionally connected in the conductive path 2, and in shunt with both reactors 20 and 21. This addition of inductive and capacitive reactors is employed in each of the cars. Thus, the car B includes the series inductive reactors 20' and 21' and the shunt capacitor 22', while the car C includes the series inductive reactors 20'' and 21'', and the shunt capacitor 22''. It is to be clearly understood that the constants of the various inductive and condensive reactors used in each of the cars are such as to constitute a transmission line network, with desired characteristics, such as proper impedance, cutoff frequency, and the like. The choice of constants depends upon the frequency range of the energy transmitted over the common path 1, 2. Those skilled in the art will understand the manner of choosing such constants so as to constitute the path 1, 2 a proper transmission network for audio modulated energy, and it is therefore not believed necessary to assign any particular values to such constants, except to point out that the L and C values of the line network should be designed to give satisfactory transmission of the desired frequency range, which may be a relatively narrow band to transmit a modulated intermediate frequency carrier or a very wide band as would be necessary to transmit the audio band. Additionally, the

- output transformer of the receiver amplifier 6 should be designed to match the impedance of the loaded transmission line 1, 2. This latter feature is also well known to those skilled in the art, and need not be referred to in any further detail.
- The constructional details of a typical radio equipped car are now to be discussed, special reference being had to car C. In this car there is provided a detector for demodulating the intermediate frequency carrier energy transmitted over the network 1, 2, the leads 30, 31 feeding the intermediate frequency energy into the second detector 32. Suitable coupling means is interposed between the transmission line and the grid of the detector. A selector circuit is also necessary where more than one channel is used. The audio frequency amplifier 33, of one or more stages, is coupled to the output of the second detector, and its output is fed into a loudspeaker line 34 and a headphone line 35. The headphone line 35 is provided with a desired number of headphones 36, or radio pillows 37, while the loudspeaker line 34 is provided with the desired number of loudspeakers 38 for use in the public spaces of car C. A power supply converter 40 is connected across the battery G, and supplies the circuits of the receiver unit components 32 and 33 with suitable energy, as shown by the dotted lines 41.
- It will be observed that all radio equipped cars, such as car C, have the battery, lighting and generator circuits effectively insulated, as in the case of the master receiver car. Each radio equipped car is wired throughout to supply a required number of speakers and headphones with the proper audio frequency energy, the lines 34 and 35 being at different volume levels. When a car, such as car B, which is not equipped for radio reception is inserted between other radio equipped cars, it is preferable to add the reactors and capacitors so that the new car can be inserted in the regular manner. But for emergency connections, a jumper cable 50 may be utilized, as shown in dotted lines, to eliminate the "regular" car from the "radio train line".
- All equipment on track, or special, trains may be equipped in this way so that cars of a train may be handled in the regular manner without special attention to the number of cars and location in a train. It will be noted that the battery load is distributed by the use of special amplifiers for each car. It is believed that the operation of the present invention will be clear from the foregoing description and the accompanying drawing.
- However, to briefly review such operation, it will be seen that the central receiver in the master receiver car is adjusted to select a particular radio broadcast program, the program being reproduced in the master receiver car A through the reproducers coupled to the amplifier 8. Simultaneously, the program is distributed to other radio equipped cars through the leads 16, 17, the program being distributed at intermediate frequency. The path comprising the conductors 1, 2, which path additionally includes the inductive and condensive reactors in each car, transmits the intermediate frequency energy throughout the train, the condensers 22, 22' and 22" permitting the flow of intermediate frequency energy around the lighting, generator and battery circuits of each car, and the path of inductive reactors in each car blocking the flow of intermediate frequency energy through the lighting, generator battery circuits of each car.
- Each coupling car B serves to transmit inter-

mediate frequency energy to a radio equipped car, and in the latter intermediate frequency energy is supplied to a second detector and an audio amplifier. It will be understood that the input circuit of the second detector in a car such as C is tuned to the intermediate frequency employed, and therefore the tuned input circuit need not be variable, but may be fixedly tuned to the particular intermediate frequency employed.

Of course, it is to be clearly understood that the present invention is not limited in any way to the distribution of intermediate frequency energy. For example, the output of the second detector could readily be distributed throughout the transmission network to radio equipped cars; indeed in that case, it would be merely necessary to employ an audio frequency amplifier in each car C. Furthermore, the invention is not limited to the use of a superheterodyne receiver in the master receiver car A, since a tuned radio frequency type of receiver can be employed in a car A, and the detector output be distributed to audio frequency amplifiers in the various cars. The essential feature of the invention resides in the utilization of the existing common battery circuit cable of the train, appropriate reactors being employed in each car, as a transmission network for program modulated energy to be reproduced in desired cars of the train.

Of course, the modulated energy distributed to the cars may be local announcements and recorded programs, as well as radio broadcast programs. The usual microphone or phonograph electric pick-up would then be used.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

1. In combination with the common direct current lighting circuit and transmission line of a train of cars, a radio receiver including an intermediate frequency amplifier in one car, means connecting the output of said amplifier to said transmission line, a second detector and an audio amplifier in a second car, means connecting the input of said detector to the opposite sides of the transmission line in said car, a direct current generator connected across the opposite sides of said line in said second car and two inductors connected in series in said line the positive terminal of said generator being connected to the common terminal of said inductors and a condenser connected across the outer ends of said inductors, said inductors and condenser being so designed as to make the transmission line within said second car a path of low impedance to energy of the intermediate frequency.
2. In combination with the direct current lighting circuit and transmission line of a train of cars, a radio receiver including an intermediate frequency amplifier in a first car, means connecting the output of said amplifier to said transmission line, a second detector and an audio amplifier in a second car, means connecting the input of said detector to said transmission line, a direct current generator in each of said named cars having its terminals connected to the opposite sides of said transmission line, two reactors connected in series in said line in each of said cars, one terminal of said generator being connected to the common

terminal of said reactors and a condenser connected across the end terminals of each pair of reactors, said reactors and condensers being proportioned and arranged to make said line a path of low impedance to currents of said intermediate frequency.

3. In combination with the direct current lighting circuit and transmission line of a train of cars, a radio receiver including an intermediate frequency amplifier in a first car, means connecting the output of said amplifier to said transmission line, a second detector having its input circuit pretuned to said intermediate frequency in a second car of said train, an audio amplifier and a sound reproducer coupled to the output circuit of said detector, connections between the input circuit of said detector and the opposite sides of said transmission line, two coils connected in series in said line in said second car, a direct current generator having one terminal connected to the common terminal of said coils and its other terminal connected to the other side of said line, a storage battery connected in shunt across the terminals of said generator and a condenser having its op-

posite sides connected to the outer terminals of said coils, said coils and said condenser being designed to efficiently transmit said intermediate frequency energy to said second detector.

4. In combination with the direct lighting current transmission line of a train of cars, a radio broadcast receiver including an intermediate frequency amplifier disposed in one of said cars, a plurality of sound reproducers disposed in another of said cars, means for connecting said amplifier and reproducers to said transmission line including a second detector having its input circuit resonant to said intermediate frequency, at least two inductive reactances located on each car and connected in series with said transmission line and a condenser connecting the outer ends of said reactances, said reactances and condenser being designed to make the transmission line within each car a path of low impedance to the intermediate frequency energy and a source of direct current potential connected to the opposite sides of said transmission line in each car.

ALVA R. HOPKINS.
